UNITED STATES PATENT OFFICE.

CHARLES E. LEWIS AND EDGAR D. ROBERTSON, OF LOS ANGELES, CALIFORNIA.

VALVE EQUIPMENT FOR OIL-WELL PUMPS.

Application filed June 8, 1927. Serial No. 197,308.

Our invention relates to deep well pumps of the plunger type intended for oil wells and more particularly to valves for such pumps.

5 The common practice in oil pumps has been to fix the working valve on the upper end of the plunger and to provide the standing valve with a rod, known as a Garbutt rod, extending upwardly therefrom through 10 a nut in the lower end of the plunger, the nut being adapted to engage the upper end of the Garbutt rod when the plunger is pulled out of the pump so as to lift the standing valve out along with the plunger. 15 The efficiency of the pump, with this arrangement of valves, often becomes greatly reduced by an accumulation of gas, between the standing valve and the working valve, which by reason of its great elasticity causes 20 a considerable amount of lost motion. It has been found advantageous, therefore, to fix the working valve on the lower end of the plunger, its proximity in that position, to the standing valve being such as to prevent 25 the accumulation of any appreciable amount of gas between the two valves.

The primary object of our invention is to provide an improved valve equipment for deep well pumps whereby exceptionally high 30 efficiency and exceptionally smooth action in the operation thereof is attained.

A further object is to provide a standing valve which is adapted for use with a plunger having the working valve fixed on its 35 lower end and means associated with the working valve for withdrawing the standing valve from the pump along with the plunger.

40 A further object is to provide a deep well pump having its working valve fixed on the lower end of the plunger thereof and means associated with the working valve for withdrawing the standing valve from the pump along with the plunger, said means being a substitute for the usual Garbutt rod.

45 Other objects and advantages will appear hereinafter and while we show herewith and will describe a preferred form of construction, we desire it to be understood that we do not confine ourselves to such preferred 50 form but that various changes and adaptations may be made therein without departing from the spirit of our invention as hereinafter claimed.

Referring to the drawings which accom-

pany this specification and form a part 55 thereof,

Fig. 1 is a fragmentary sectional view of an oil well pump equipped with our improved valves, the working valve being shown in section and the standing valve in 60 elevation.

Fig. 2 is an enlarged sectional view of the standing valve shown in Fig. 1, the section being taken on line 2—2 of that figure.

Fig. 3 is a plan view or upper end view 65 of the standing valve shown in Fig. 2, with the auxiliary polished rod shown in section.

Fig. 4 is a transverse sectional view of the standing valve shown in Fig. 2, taken on 70 line 4—4 of that figure.

Considered more in detail the drawings will be seen to show a pump having the usual plunger 10 adapted to reciprocate in the usual working barrel 11 connected in the usual pump tubing 12, the plunger being 75 connected to the usual polished rod 13 by a sand head 14, with streamline oil outlets, which is screwed into the upper end of the plunger against a jam nut 15.

A ball valve of the closed type comprising 80 a blind cage 16 with a cross-bar 17 to limit the upward movement of the ball 18 and a cage coupling 19, with a ball seat, in its upper end, is screwed into the lower end of the plunger to serve as a working valve. A 85 cage 20 is screwed onto the lower end of cage coupling 19 and an auxiliary polished rod 21 smaller than the regular polished rod 13 is screwed into cage 20 so as to extend 90 downwardly therefrom.

The standing valve 22 is a modified form 95 of the valve shown in our application, filed Sept. 13, 1926, under Serial No. 184,987, for a patent on a relief valve for deep well pumps. It consists of a tubular body 23, 100 adapted to seat in the pump tube coupling 24, below the plunger of the pump, said body having a sleeve 25 in the upper end thereof which is held in concentric relation thereto by regularly spaced radial arms or partitions 26 so as to provide vertical openings 27 between the body 23 and sleeve 25 through which oil may flow freely. Sleeve 25 is internally screw-threaded and two sleeves 28 and 29, having a diameter which 105 conforms to that of polished rod 21, are screwed one into the upper and the other into the lower end thereof, as shown in Fig.

2. The upper ends of partitions 26 are cut away somewhat so that an annular groove 30 is formed at the upper end of the valve body, between sleeve 25 and the body proper, 5 and a ring flapper 31 having beveled faces 32, adapted to seat in groove 30, encircles guide sleeve 28 and serves as the valve closure. A stop nut 33 and a lock nut 34 are screwed on sleeve 28 above flapper 31 to adjustably limit its working space. Radial grooves 35 are cut in the upper end of ring flapper 31 to provide for equalization of pressure on the inner and outer sides thereof. The upper and lower ends of valve body 15 23 are extended to form screw-threaded nipples 36 and 37, respectively, and an upper cage 38 and a lower cage 39 are screwed thereon, the upper one extending upwardly to the end of guide sleeve 28 and the lower one extending downwardly to the end of guide sleeve 29, and each embracing said sleeve ends respectively.

The standing valve thus constructed is adapted to rest in its seat in coupling 24 with 25 polished rod 21 extending downwardly through guide sleeves 28 and 29 thereof. The length of polished rod 21 is such that a washer 40 and retaining nuts 41, screwed on its projecting lower end, reciprocate in 30 the pump tubing below lower cage 39 while the plunger is operating and come in contact with cage 39 only when the plunger is being withdrawn from the pump or is being inserted into it.

35 The operation of the valves has been suggested in the description thereof. Polished rod 21 works in sleeves 28 and 29 of the standing valve. As the plunger moves upwardly oil is drawn through the standing valve into the space between it and the working valve, flapper 31 lifting off from its seat to allow it to pass. When the plunger starts on its downward stroke flapper 31 drops back and closes the standing valve whereupon oil flows through the working valve, ball 18 lifting off from its seat and allowing free passage thereto and falling back on its seat when the plunger starts on another upward stroke. Auxiliary polished rod 21 40 serves to effect an exceptionally steady action of the plunger when operating and also serves as a substitute for the usual Garburt rod to withdraw the standing valve from the pump along with the plunger. The two 45 cages 38 and 39 on the standing valve serve the double purpose of holding guide sleeves 28 and 29 in rigid alignment and also as a

protection from possible injury to the working parts of the standing valve when being removed from or inserted into the pump. 60

It will be seen, therefore, that a pump equipped, as shown, with our improved valves and auxiliary polished rod will operate with exceptional smoothness and efficiency and can be changed or repaired with 65 the usual facility.

Having thus illustrated and described our invention, we claim:

1. A standing valve for deep well pumps comprising a tubular body adapted to seat 70 in a pump-tube coupling, a concentric sleeve held in said tubular body by radial partitions so as to form a series of vertical openings terminating in an annular passage in the upper end thereof; guide sleeves fixed 75 in said concentric sleeve so as to extend above and below said tubular body, said guide sleeves being adapted to receive a polished rod extending from a pump plunger through the valve; a ring flapper encircling the upper of said guide sleeves and serving as a closure to said annular passage; a stop nut adjustably fixed on said upper guide sleeve to limit the movement of said flapper and cages fixed on the upper and lower ends 80 of said tubular body so as to embrace the ends of said guide sleeves.

2. In combination with an oil well pump a standing valve comprising a tubular body seated in the pump-tube coupling, said body having a series of vertical ducts whose upper ends terminate in a common annular groove, concentric with the axial bore of the tubular body; guide sleeves fixed in the central bore of said tubular body, so as to 95 extend beyond its upper and lower ends; a ring flapper encircling the upper guide sleeve, said flapper being adapted to seat in said annular groove and to serve as a closure to said vertical ducts; an adjustable stop-nut, on the upper guide sleeve, adapted to limit the movement of said flapper; protecting cages fixed on the upper and lower ends of said tubular body so as to embrace the free ends of said guide sleeves; a polished rod working through said guide sleeves, said polished rod being attached to the plunger of the pump, and means, on the lower end of said polished rod, for engaging the lower protecting-cage so as to withdraw the standing valve from the pump along with the plunger. 100
